Primary Examiner — Brett Miller*Assistant Examiner* — Rani J Abdallah(74) *Attorney, Agent, or Firm* — Michael Best & Friedrich LLP(57) **CLAIM**

The ornamental design for a bottle, as shown and described.

DESCRIPTION

FIG. 1—Top, front, right side perspective view, the bottle being rotationally symmetric;

FIG. 2—Front elevation view;

FIG. 3—Left side elevation view;

FIG. 4—Top plan view; and,

FIG. 5—Bottom plan view.

The even broken lines represent portions of the bottle that form no part of the claimed design. Any surfaces inside the bottle form no part of the claimed design.

1 Claim, 3 Drawing Sheets(56)
